NEEDLE VALVE MECHANISM

Oliver C. Ritz Woller, Chicago, Ill.

Application June 26, 1931, Serial No. 547,158

13 Claims. (Cl. 251—44)

My invention relates to needle valve mechanism and is particularly designed for use in connection with an adjustable spray jet in a well-known type of carburetor. It is one of the objects of my invention to provide an improved form and arrangement of parts whereby the valve mechanism shall be enabled to stand up through long periods of use and remain effective in every way regardless of frequent and unnecessary or unskilled adjustments.

It is one of the objects of my invention to produce an arrangement of this type in which the required amount of play is provided for enabling a user to move the needle adjusting means through the complete range of its action in the direction for cutting down the flow of gasoline without danger of injuring the needle valve, either in the way of bending the needle or in the way of spreading the mouth of the nozzle into which the needle is pressed. To this end, it is one of the objects of my invention to provide an improved arrangement by which the needle is held yieldingly in its operative position through the medium of a spring or other yielding means which normally holds the needle in the desired operative position for any proper adjustment of the parts but which is adapted to yield so as to prevent damage to the parts when an improper adjustment is made such as would otherwise press the needle forward too far and too forcibly into engagement with its cooperating parts.

It is another object of my invention to provide an improved arrangement of packing means in connection with an adjustable mechanism of this type whereby leakage of gasoline at the valve may be prevented.

It is another object of my invention to improve devices of this type in sundry details hereinafter pointed out. The preferred means by which I have accomplished my several objects are illustrated in the drawing and are hereinafter specifically described. That which I believe to be new and desire to cover by Letters Patent is set forth in the claims.

In the drawing,—

Fig. 1 is a central vertical section through a needle valve mechanism embodying my improved construction and arrangement; and

Fig. 2 is a view similar to the lower portion of Fig. 1 but showing an adjusted position of certain of the parts.

Referring to the drawing, 10 indicates a block of metal, being in the arrangement shown a thickened part of the wall of a carburetor. The block 10 is bored out at its bottom face to pro-

vide a chamber 11 therein adapted to receive gasoline or other liquid fuel through a port 12 from any suitable source. At one side of the chamber 11, a sleeve 13 is provided opening at its inner end into the chamber, such sleeve being mounted in position by means of an enlarged portion 14 which is connected by means of screw threads with the wall of an opening from the chamber 11, a gasket 15 of any suitable type being preferably provided for forming a tight joint between the parts. The outer end portion of the sleeve 13 is tapered inwardly so as to provide a tapered seat for a needle 16 which extends into the sleeve 13 so as to close the opening at the end of the sleeve.

The rear end of the needle 16 is mounted in a slide bearing at the forward end portion of a head member 18, the rear end of the needle 16 having an enlarged portion 17 adapted to seat against the shoulder at the inner end of said bearing portion, the rear end portion of the head 18 having a central opening therethrough of larger size than that through said bearing portion. A coiled spring 19 is mounted in the bore of the head 18 in rear of the needle 16, the forward end of the spring bearing against the enlarged end portion of the needle, and the rear end of the spring bearing against a knurled closure member 20 having a pressed fit by means of a lug 21 in the bore of the head 18, a gasket 22 being employed upon the lug 21 opposite the end of the head 18. The arrangement is such that the head 18 may be readily manipulated through the medium of the knurled member 20, and the spring 19 is normally compressed so as to hold the needle 16 in its fully projected position as shown in Fig. 1. The spring 19 is adapted, however, to yield backwardly so as to permit movement of the head 18 forwardly with respect to the pin 16 whereby the head 18 may be given excessive forward movement without forcing the forward end of the pin or valve 16 through the tapered end of the sleeve 13 far enough to spread or expand the wall so as to enlarge the size of the opening.

In the construction shown, the head 18 is adjustably mounted in its operative position as shown in Fig. 1 by means of a bushing or nipple 23 which is secured by means of screw threads in the outer end of the opening providing the chamber 11, a gasket 24 of any approved type being preferably provided between the block 10 and an annular rib 25 on the outer face of the nipple 23 so as to provide a tight joint between the parts. The head 18 in the construction

shown is adjustably mounted within the nipple 23 by means of screw threads, the arrangement being such that when the head 18 is rotated through the medium of the knurled member 20 such head 18 is moved forwardly toward the sleeve 13 or backwardly away from such sleeve as may be desired.

For providing a tight joint between the head 18 and the nipple 23, I have provided packing means in the form of a plurality of gaskets 26, preferably of leather, such gaskets being mounted about the head 18 so as to engage the end of the nipple 23. A comparatively heavy spring 27 is mounted about the head 18 in rear of the packing washers 26, bearing at its forward end against said washers, but with a metal washer 28 interposed, the spring 27 bearing at its rear end against the end wall of a cap 29 which surrounds the spring and washers, the forward end of the cap 29 having a tight pressed fit upon the rear end of the nipple 23. The arrangement and proportions of the parts are such that under normal conditions as shown in said Fig. 1 the spring 27 presses the packing washers 26 firmly against the 25 sides of the head 18 and against the end of the nipple 23 so as to provide a tight joint between such parts, such joint being adapted to remain effective at all times upon adjustment of the head 18 in either direction with respect to the nipple 23. The spring 27 is also of such strength as to push the packing washers forward into operative closure position when the washers shrink or otherwise tend to loosen with respect to the parts.

With the parts in the condition as shown in Fig. 1, upon the rotation of the head 18 through the medium of the knurled member 20 the head 18 may be moved forwardly toward the sleeve 13, serving to adjust the forward end of the needle 16 with respect to the opening at the end of the sleeve 13. The arrangement is such that the needle 16 moves either forwardly or backwardly with the head 18 for effecting the desired adjustment of the effective size of the opening at the end of the sleeve. When, however, the end of the needle 16 is moved to the limit of its normal forward motion with respect to the sleeve 13, there is no danger that continued adjustment of the head 18 in the direction for producing forward movement of the needle shall result in undue pressure of the needle against the seat at the end of the sleeve 13, since under such circumstances the spring 19 yields backwardly with respect to the head 18 so as to permit the needle to remain stationary. The arrangement is such that the head 18 might be projected forwardly a considerable distance beyond the forward end of the nipple 23 without having any effect upon the needle 16 other than to increase slightly the pressure of the spring 19 thereon.

In Fig. 2 I have shown the parts in position similar to that illustrated in Fig. 1 except that in Fig. 2 the bearing portion at the forward end of the head 18 is standing in adjusted position with respect to the enlarged portion 17 of the pin 16, the spring 19 having yielded backwardly to the necessary extent for permitting such change in position.

By the use of my improved construction, I am enabled to adjust the needle valve member 16 to the desired position with respect to the sleeve 13 for controlling the effective size of the opening at the end of the sleeve so as to regulate with a high degree of nicety the amount of gasoline permitted to escape from the sleeve under the influence of the suction of the engine with which

the carburetor is designed to act. Such adjustment can be effected without danger of injury to any of the parts. The arrangement is such that there is no danger of leakage of gasoline at any time after the initial proper adjustment of the mechanism.

While I prefer to employ the form of device as shown in my drawing and as above described, it is to be understood that my invention is not limited thereto except so far as the claims may be so limited by the prior art.

I claim:

1. In a needle valve mechanism, the combination of a nipple adapted for mounting in the wall of a carburetor and having an opening therethrough, a comparatively long slender needle valve member having its rear end portion located within the opening in said nipple and comprising a pointed forward end portion extending beyond the nipple for partially closing the opening at the inner end of a spray sleeve of the carburetor, yielding means engaging said needle valve member for pressing it forwardly in said nipple, and means carried by said nipple for pressing the spring forwardly and comprising a part adjustable forwardly with respect to the nipple for limiting the forward movement of the needle valve member with respect to said nipple.

2. A needle valve mechanism, comprising in combination a chamber having an outlet opening defined by an expansible wall portion constituting a seat for the valve through which opening gasoline is adapted to escape from the chamber, a needle valve, and adjustable means comprising a yielding member adapted normally to project the forward end portion of said needle valve longitudinally through said opening and adapted to permit said yielding member to give backwardly upon excessive movement of the adjustable means.

3. A needle valve mechanism comprising in combination a chamber, a sleeve leading from one side of said chamber and having a restricted tapered opening at its outer end, a needle valve extending through the sleeve and having a tapered outer end portion adapted to close the outer end of said sleeve, and adjustable means for moving said needle longitudinally of said sleeve for regulating the effective size of the opening in said sleeve about the needle and comprising yielding means adapted to give for permitting the needle to remain stationary upon continued adjustment after the needle is brought into operative closing engagement with the end portion of said sleeve.

4. A needle valve mechanism comprising in combination a chamber, a sleeve leading from one side of said chamber and having a restricted tapered opening at its outer end, a nipple secured by screw threads in the opposite side portion of said chamber having an opening therethrough in alignment with said sleeve, a needle valve in the opening in said nipple and extending into said sleeve, and adjustable means for moving said needle lengthwise of said sleeve and comprising a part adapted to yield backwardly for permitting the needle to remain stationary upon continued adjustment after said needle is brought into operative closing engagement with the end portion of said sleeve.

5. A needle valve mechanism comprising in combination a chamber, a sleeve leading from one side of said chamber and having a restricted tapered opening at its outer end, a nipple secured by screw threads in the opposite side portion of

said chamber having an opening therethrough in alignment with said sleeve, a head mounted by means of screw threads in the opening in said nipple, a needle valve mounted in said head and movable longitudinally with respect thereto, and spring means serving normally to hold said needle moved to the limit of its motion with respect to said head but adapted to yield for permitting the needle to remain stationary upon further adjustment after said needle is brought into operative closing engagement with the end portion of said sleeve.

6. A needle valve mechanism comprising in combination a nipple having an opening therethrough, a needle valve in said opening, means comprising a spring for holding said needle valve in operative position in said opening, packing means in operative position between said nipple and said needle holding means, and a spring for holding said packing means yieldingly in operative position.

7. A needle valve mechanism comprising in combination a nipple having an opening therethrough, a head adjustably mounted in said opening, a needle valve mounted in said head and movable longitudinally with respect thereto, spring means for pressing said needle valve forward with respect to said head but adapted to yield backwardly, packing means surrounding said head opposite the end of said nipple, and spring means for holding said packing means yieldingly in operative engagement with said head and said nipple.

8. A needle valve mechanism comprising in combination a sleeve having an opening at one end of substantially smaller size than that of the sleeve, a needle valve mounted in said sleeve and having a tapered portion adapted by adjustment longitudinally of the sleeve to vary the effective size of the opening about the needle, and means for pressing said needle towards and partially through said opening and comprising a part adapted to yield backwardly with respect to the remainder of the pressure means when the needle has reached the normal limit of its motion with respect to the sleeve.

9. A needle valve mechanism comprising in combination a sleeve having an opening at one end of substantially smaller size than that of the sleeve, a needle valve mounted in said sleeve and having a tapered portion adapted by adjustment longitudinally of the sleeve to vary the size of the opening about the needle, a member adjustable toward and from said sleeve adapted by engagement with said needle valve to limit its movement along the sleeve into operative closure position therein, and yielding means tending to move said needle valve in the direction for closing said opening when said adjustable member is moved toward the sleeve but adapted to yield backwardly when the needle valve has reached its operative closure position in said sleeve.

10. A needle valve mechanism comprising in combination a chamber, a sleeve leading from one side of said chamber and having a restricted tapered opening at its outer end, a head adjustably secured in the opposite side portion of said chamber and having an opening therethrough in alignment with said sleeve, a needle valve in said opening, and spring means for pressing said needle forwardly with respect to said head but adapted to yield backwardly for permitting the needle to remain stationary upon continued adjustment of

the head after the needle has been brought into operative closing engagement with the end portion of said sleeve.

11. A unit type of needle valve mechanism for use in the spray jet of a carburetor, comprising in combination a nipple member having an opening therethrough and provided with screw threads adapted by engagement with the threads of the socket in the wall of the carburetor through which gasoline is introduced into the carburetor to support the nipple in fixed position on the carburetor, a needle valve in said opening and projecting forwardly therefrom and having a sharp end portion for operative engagement with the tapered opening at the end of the spray sleeve of the carburetor, and adjustable means including a yielding member adapted normally to project said needle valve forwardly longitudinally of the opening in said nipple and adapted when said needle valve reaches the limit of its normal forward movement to permit said yielding member to yield backwardly.

12. A unit type of needle valve mechanism for use in the spray jet of a carburetor, comprising in combination a nipple member having an opening therethrough and provided with screw threads adapted by engagement with the threads of the socket in the wall of the carburetor through which gasoline is introduced into the carburetor to support the nipple in fixed position on the carburetor, a head adjustably mounted in the opening in said nipple and having in turn an elongated opening therein open at its forward end, a needle valve member mounted in said opening in the head and extending forwardly therefrom beyond the nipple member and having a sharp end portion for operative engagement with the tapered opening in the end of the spray sleeve of the carburetor, means for holding said needle valve member from escaping forwardly from said opening in the head, and spring means adapted normally to hold said needle valve member at the limit of its movement forwardly in said head but adapted to yield backwardly when the needle valve member is by the adjustment of said head brought to the limit of its normal forward movement with respect to said spray sleeve.

13. A unit type of needle valve mechanism for use in the spray jet of a carburetor, comprising in combination a nipple member having an opening therethrough and provided with screw threads adapted by engagement with the threads of the socket in the wall of the carburetor through which gasoline is introduced into the carburetor to support the nipple in fixed position on the carburetor, a comparatively long slender needle valve member mounted at its rear end portion in the opening in said nipple and extending some little distance forwardly therefrom for partially closing the tapered discharge opening at the end of the spray sleeve leading inwardly from said socket, and adjustable means including a yielding member adapted normally by pressure on said needle valve member to move said member forwardly in said opening in said nipple and adapted when said needle valve member reaches the normal limit of its forward movement through said tapered opening in the sleeve to permit said yielding member to yield backwardly so as to avoid enlargement of the opening in the sleeve by said needle valve member.

OLIVER C. RITZ WOLLER.
